METALWORKING MACHINE

John M. Christman, Detroit, Mich., assignor to
 Packard Motor Car Company, Detroit, Mich.,
 a corporation of Michigan

Application September 19, 1934, Serial No. 744,655

9 Claims. (Cl. 153-2)

This invention relates to metal working machines and more particularly to machines for bending and finishing formed metal strips.

An object of the invention is to provide a machine in which formed metal strips can be readily bent and finished to smooth out bending wrinkles.

Another object of the invention is to provide a machine in which a fixture can be readily adjusted so that a bending device and a wrinkle smoothing device can be successively applied to operate upon formed metal strip material held thereby.

A further object of the invention is to provide a machine on which a U-shaped strip of metal can be bent longitudinally and then smoothed to remove wrinkles therein.

A still further object of the invention is to provide a metal working machine in which a work table can be readily indexed to be cooperatively related with bending means or with ironing means.

Other objects of the invention will appear from the following description taken in connection with the drawing, which forms a part of this specification, and in which:

Fig. 1 is a plan view of a metal working machine incorporating the invention;

Fig. 2 is an end elevational view of the same partially broken away and in section to show the straightening rollers in applied relation.

Referring now to the drawing by characters of reference, 10 indicates the bed of a metal working machine having supporting legs 11. Fixed on the bed are supporting base plates 12 and 13.

Rotatably mounted on the base plate 12 is means for supporting metal strip material during bending and ironing operations thereon. Such means consists of a table 14 resting on the bed plate 12 and having a pivot pin 15, projecting from the bed plate, extending therethrough. The table is secured against axial displacement by means of a nut 16 engaging the upper threaded end of pivot pin 15.

One or more forms 17 are fixed to the table by means of bolts 18 and a portion of such forms extends beyond the table and is curved in the shape in which it is desired to bend a strip of metal. In the present instance, these forms 17 are preferably flat and rest directly on the table with their free faces projecting beyond the table shaped to take a strip of metal material formed angular in cross section preferably in U-shape. These strips are fitted over the projecting faces

of the forms and are secured thereto by clamps as indicated at 19. The table and the clamps are formed with angular faces which are complementary when the clamps are in position to secure the strips. The clamps are also each formed with a slot 21 through which extends a stud 22 upon which a nut 23 is threaded to secure the clamp in position. By means of this slot, the clamp can be removed when the nut is backed off so that the strip can be removed from the form without entirely unscrewing the nut.

Mounted on the base plate 13 is a device for bending the metal strips secured to the forms by the clamps 19. Such device includes a plate 24, pivotally mounted on a bolt 25 secured to the base and the bed plate 13. An arm 26 is welded to the plate 24 and forms therewith a lever which can be swung manually on the pivot 25 by an operator to perform a bending operation. The arm 26 terminates at one end in a roll boss 27 on which are mounted rollers 28, the rollers being held in position by studs 29 extending therethrough and engaging the boss. Between the rollers and the strip of material held on the form there is arranged a follow bar 30 having a plane face 31 contacting with the rollers and a grooved face 32 into which the formed metal strips lie during bending.

After a strip is telescopically moved onto the projecting portion of a form and secured by the clamp 19, the table is rotated to a position where the recess in the follow bar can fit over the strip projecting beyond the end of the form whereupon swinging movement of the bending device will cause the follow bar to travel around the curved face portion of the form and bend the metal strip thereagainst. The rollers maintain the follow bar at right angles to the operating lever and the design of the recess in the follow bar is such that the base of the formed strip will be pressed against the outer face of the form and the side flanges of the strip will be pressed against the upper and lower faces of the form. When one end of the strip has been bent around the form, then the position of the table is shifted so that the same operation can be repeated on the other end of the strip.

In order that the table can be fixed in the four positions required for the four bending operations when there are two forms, I provide a pair of oppositely disposed holes 33 in the table and a pair of oppositely disposed holes 34 in the forms 17. The bed plate is provided with a hole 35 with which any one of the holes 33 and 34 can be arranged in alignment upon rotation of the table. 65

An index plunger or anchor member 36 is inserted through the aligned holes to fix the table to the bed. This plunger is provided with a handle 37 in order that it may be readily grasped for application to or removed from the table.

The bent portions of the metal strips lying adjacent the upper and lower surfaces of the forms become wrinkled during the bending operation 10 and associated to cooperate with the table while the strips are still held on the forms is arranged an ironing device for smoothing out such wrinkles. Prior to moving the table in position so that the ironing device can cooperate therewith, I preferably secure the bent ends of the strips against the forms by clamping means. In the present invention, a pair of ears 38 is secured to and project upwardly from the table adjacent each end of the forms and between each of such pair of ears 20 is pivotally mounted a clamp lever 39 having an end which can be swung down to press the bent end of the strip against the form. Associated with each of the clamp levers 39, I provide securing means which in the present instance consists 25 of a pin 40 rotatably mounted so that the flanged portion 41 of the head 42 can be swung over the lever. When the straight face 43 of the pin head lies adjacent the lever, then the lever can be swung up or down, that is, out of or into clamping 30 relation with the end of the bent strip.

When the strips have been bent around the forms and their ends are suitably clamped to the forms, the table is rotated into a position preferably opposite the bending device where each 35 bent end can be smoothed out by the ironing device.

Fixed to reciprocate on the bed plate 10 is a housing comprised of three sections 44, 45 and 46 which are secured together by bolts 47. A portion 40 of the housing adjacent the table is recessed as indicated at 48 so that it can telescope one end of a form when moved toward the table.

Ironing means is arranged in the recess which in the present instance consists of roller segments 49 and 50 spaced apart so that they will engage the surfaces of the bent strip lying against the upper and lower faces of the form. These roller segments form a part of shafts 51 and 52 which extend through the sections 44 and 46 of 50 the housing and are rotatably mounted therein. A spring 53 is fixed to an end of each shaft and to the adjacent housing section to normally rotate the shafts so that the roller segments are moved toward the open end of the recess in the 55 housing.

A pair of guide members 54 are fixed on the bed plate 10 and the housing is grooved at each side as indicated at 55 so that the end portions thereof overlie the guides. The roller housing 60 is reciprocated preferably by power means. In the present instance, side plates 56 are secured to the end portion of the bed plate and have fixed at their ends an end plate 57 to which a cylinder head 58 is secured by bolts 59. Located in 65 the cylinder is a piston 60, adapted to be actuated by compressed air or similar power means, having a shaft 61 extending through the cylinder head, the end plate 57 and secured at its forward end to a bar 62 by means of a bolt 63. This bar 70 62 is secured to the roller housing by bolts 64 and is arranged to slide on the upper wall of the side plates 56.

In order to limit the movement of the housing in a direction toward the table, the side plates 75 are provided with upstanding portions 65 which

serve as stop members for the bar 62, it being understood that the housing is of such width that it can be reciprocated between the side plates 56. In the position shown in the drawing, the ironing operation has just been completed and as the housing is moved toward the left, the roller segments will be moved toward the open end of the recess, the springs 53 assisting in such movement.

The roller segments are of course designed so that they will exert pressure against the faces of the bent portions of the strips lying adjacent the upper and lower surfaces of the forms. It will be understood that a single roller segment could be used with angle strips to produce the same ironing effect thereupon as that produced by two rollers on two faces of a formed strip of U-section. Each end of the strips bent around the forms is moved successively into position where the roller segments can engage therewith to iron out the wrinkles formed by the bending operation and the same anchor means for securing the strips to the table during the bending operations are utilized for this purpose. When the ironing operations have been completed on the ends of a bent strip, the nut 23 is unscrewed so that the 25 clamp 19 can be removed thus allowing the strip to be moved horizontally from the form. The strip so bent and ironed is finished so that further operation to provide smooth surfaces is not required.

Through the arrangement of the work holder with the bending and ironing devices, an operator can efficiently bend and finish formed metal strips while standing in one position.

Although the invention has been described in connection with a specific embodiment, the principles involved are susceptible of numerous other applications which will readily occur to persons skilled in the art. The invention is therefore to be limited only as indicated by the scope of the appended claims.

What I claim is:

1. In a metal working machine, the combination of a form on which a channel shaped metal strip is held, and an ironing device comprising a reciprocable housing and a pair of roller segments carried by the housing, said rollers being arranged to roll against opposite faces of the strip on said form when said device is reciprocated.

2. In a metal working machine, the combination with a work holder, of an ironing device comprising a reciprocable housing, a work ironing roller mounted in said housing in a relation to bear against work on the holder when the housing is reciprocated, and spring means associated with said roller and housing tending to maintain the roller in a predetermined position of its rotation.

3. A metal working machine comprising a base, a bending device carried by said base, a smoothing device carried by the base, said devices being arranged in spaced relation, a table rotatably mounted on the base intermediate said devices, a form on the table for receiving an angular strip of metal, and means associated with the form for clamping the angular strip metal thereagainst, said table being movable to place said form in cooperative relation with either device for a forming operation on the strip of metal held thereon.

4. A metal working machine comprising a bending device movable in a curved path, a smoothing device having a pair of spaced rollers, a shiftable table, a form fixed on said table for

5 receiving a straight length of channel shaped metal, said form having a straight portion over which the channel shaped metal fits and a curved portion over which a portion of the metal strip 5 is to be bent, and means for clamping the length 10 of metal against the straight portion of said form, said bending device cooperating with the form to bend the clamped metal around the curved portion of the form, and the rollers of said 15 smoothing device cooperating with the form to press the wrinkles out of the two faces of said metal against the top and bottom faces of the form.

6 5. A metal working machine comprising a 15 base, a bending device carried by said base, a smoothing device carried by the base, said devices being arranged in spaced relation, a table 20 rotatably mounted on the base intermediate said devices, a form on the table for receiving an angular strip of metal, means associated with the form for clamping the angular strip metal 25 thereagainst, said table being movable to place said form in cooperative relation with either device for a forming operation on the strip of metal held thereon, and anchor means securing said table to said base when the form is in a cooperative position with either device.

7 6. A metal working machine comprising a bending device movable in a curved path, a 30 smoothing device having a pair of spaced rollers, a shiftable table, a form fixed on said table for receiving a straight length of channel shaped metal, said form having a straight portion over which the channel shaped metal fits and a curved 35 portion over which a portion of the metal strip is to be bent, means for clamping the length of

metal against the straight portion of said form, said bending device cooperating with the form to bend the clamped metal around the curved portion of the form, the rollers of said smoothing device cooperating with the form to press the wrinkles out of the two faces of said metal 5 against the top and bottom faces of the form, and clamp means for holding the bent portion 10 of the strip against the form during the smoothing operation.

8 7. In a metal working machine, the combination with means for supporting and shifting work from one station to another station, of a device movable at one station to cooperate with said means for bending work carried thereon, and a 15 device at the other station movable in cooperative relation with said means for pressing wrinkles from the bent work.

9 8. In a metal working machine, the combination with movable means for supporting and shifting work from one station to another station, of a device at one station adapted to cooperate with said means for bending work carried thereon, and a device reciprocable at the other station in cooperative relation with said 20 means for removing wrinkles from the bent work.

10 9. In a metal working machine, the combination with movable means for supporting and shifting work from one station to another station, of a device swingable at one station to cooperate with said means for bending work carried thereon, and a device movable at the other station to cooperate with said means for removing wrinkles from the bent work.

JOHN M. CHRISTMAN.
